(57) **CLAIM**

The ornamental design for a weapon accessory mount, as shown and described.

DESCRIPTION

FIG. 1 is a front elevation view of the weapon accessory mount, showing my novel design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a perspective view of the weapon accessory mount of the present invention; and,

FIG. 8 is a perspective view of a double-sided weapon accessory mount of the present invention as shown attached to a rifle barrel.

The broken lines shown in FIG. 8 are for illustrative purposes only and form no part of the claimed design.
